(57) **CLAIM**

The ornamental design for a self-contained water fountain, as shown and described.

DESCRIPTION

FIG. 1 is a top plan view of the self-contained water fountain of the present invention;

FIG. 2 is a bottom plan view thereof;

FIG. 3 is a front elevation view thereof, the rear and side elevation views being identical thereto; and,

FIG. 4 is a front perspective view of the self-contained water fountain of the present invention.

The simulated rock base shown in broken lines is for illustrative purposes only and forms no part of the claimed design.
